[57] CLAIM

The ornamental design for a decorative drink coaster, as shown and described.

DESCRIPTION

FIG. 1 is a front perspective view of a decorative drink coaster showing my new design;

FIG. 2 is a top plan view thereof;

FIG. 3 is a bottom plan view thereof;

FIG. 4 is a side elevational view thereof, the remaining three side elevational views being substantially identical thereto;

FIG. 5 is a front perspective view of a modified embodiment of FIG. 1;

FIG. 6 is a top plan view of FIG. 5;

FIG. 7 is a bottom plan view of FIG. 5; and

FIG. 8 is a side elevational view of FIG. 5, the remaining three sides elevational views being substantially identical thereto.

FIG. 1

FIG. 2

FIG. 3

FIG. 4

FIG. 5

FIG. 6

FIG. 7

FIG. 8
